J. Q. COOKE

PROPULSION APPARATUS

Filed Feb. 23, 1926

UNITED STATES PATENT OFFICE.

JOHN O. COOKE, OF DAYTONA BEACH, FLORIDA.

PROPELLION APPARATUS.

Application filed February 23, 1926. Serial No. 90,135.

This invention is an apparatus for propelling vessels of all types.

One of the objects of the invention is to provide an apparatus of simple construction, by means of which a maximum power may be developed and utilized for propelling a vessel. A further object is to provide a propeller of the chain type to be mounted on the sides of the hull of a vessel, said propeller being capable of operating in either direction to effect forward or reverse travel of the vessel, or to steer the same at will. A further object is to provide a chain type propeller having paddle blades of simple construction, which are firmly braced to effectively react against water irrespective of the direction of travel.

The invention will be hereinafter fully set forth and particularly pointed out in the claims.

In the accompanying drawing:

Figure 1 is a side elevation of a boat equipped with a propeller apparatus constructed in accordance with the invention. Figure 2 is a transverse sectional view on the line 2—2, Figure 1, parts being broken away. Figure 3 is a detail view illustrating one of the propulsion paddles.

Referring to the drawing, 10 designates the hull of a vessel which may be of any preferred type. As shown the same is provided with a deck 11, the sides of which overhang the hull as indicated at 12. The propellers are located on each side of the hull beneath the overhanging portions of the deck. The propellers may be driven in any suitable or desired manner, but for purposes of illustration drive shafts 13 and 14 are employed, each carrying sprocket wheels 15. As shown, the shafts 13 and 14 are provided with pinions *a*, *b*, respectively, which mesh with the differential pinion *c*, carried by a casing or support which is provided with the main drive pinion *d* of a conventionally illustrated differential gearing. A drive pinion *e* on shaft *f* meshes with the pinion *d* which is loosely mounted on the shaft 14. Power is supplied to the shaft *f* by means of any desired form of prime mover in a manner well understood in the art.

Engaging the sprockets of each set of wheels 15 is a sprocket chain 17, consisting of two parallel members, each formed of links 18, pivotally connected to cross shafts 19. The sprocket wheels 15 have recesses which engage said cross shafts to effect the

drive of the chain. Pivots mounted at one end on each cross shaft 19 are pairs of arms 20, paddle blades 21, 22, of wood or other suitable material being bolted to said arms. The outer end of each paddle blade 22 is loosely engaged by the free ends of a pair of brace rods 23, the other ends of which are each pivoted to a link 18, as indicated at 24. Said free ends of the brace rods 23 extend through the respective blades, and relative movement of the blades and the brace rods is limited by stops, such as nuts 25 on the free ends of said rods.

In operation the drive shafts 13 are rotated from any suitable power source through the gearing 16, and by reason of the engagement of the sprockets 15 with the chain 17 causes said chain and the blades carried thereby to travel forwardly or rearwardly, as desired. The rearward travel may be effected by utilizing any desired type of clutch or gearing, and in a like manner the sprocket wheels 15 on one side may be rotated independently of those on the other side of the vessel. As the chains are caused to travel, the blades 21 and 22 dip into and push against the water, and by reason of the reaction developed by their travel through the water, the vessel is propelled.

It will be noted that when the blades 21 and 22 are in propelling position the two blades of each pair abut against each other, so that blades 21 will cause forward travel of the vessel and blades 22 will cause rearward travel according to the direction of travel of the sprockets. When said blades travel around the sprocket wheels, due to the difference in angular relation of the links 18 at these points, the two blades will separate into an approximately right angular relation until they pass over the sprocket, whereupon as the links are again brought into alignment the blades are again brought together.

The advantages of the invention will be readily understood by those skilled in the art to which it belongs. It will be particularly noted that by reason of the sprocket and chain arrangement, together with the disposition of the blades, a maximum propelling power is obtained. An important advantage lies in the arrangement of the blades in pairs, so that one or the other blade of the pair acts to drive the vessel, depending upon which direction the chain is caused to travel. Therefore, whichever blade is operated as a

propeller is braced firmly against the strains encountered in connection with the work to be performed. Where the vessel is constructed with an overhanging deck, as shown, the same serves to protect the propeller from damage.

Having thus explained the nature of the invention and described an operative manner of constructing and using the same, although without attempting to set forth all of the forms in which it may be made, or all of the forms of its use, what is claimed is:—

1. A propulsion apparatus of the character described comprising sprocket wheels, sprocket chains formed of pivotally connected links engaging said wheels, pairs of paddle blades each pivotally connected at one end to said chain, means for causing the free ends of the paddles to separate as said 15 paddles pass around the sprocket wheels, and driving means operatively connected with one of said sprockets.

2. A propulsion apparatus of the character described comprising a driving sprocket and a driven sprocket, a sprocket chain connecting said sprockets and formed of pivotally connected links, blades arranged in pairs and each having one end pivotally mounted upon a pivotal connection of said 25 links, brace rods extending from said links to the blades and having means for limit-

ing movement of the free ends of the blades in one direction, the brace rods of each pair extending in opposite directions, whereby the free ends of the blades will separate as 35 they travel around the sprocket wheels.

3. A propulsion apparatus of the character described comprising a driving sprocket wheel, a driven sprocket wheel, a sprocket chain engaging said wheels and formed of 40 spaced apart members, each member consisting of a plurality of links, pivot rods connecting said links and also connecting said members, paddle blades arranged in pairs, the blades of each pair being pivoted at one 45 end on a common pivot rod, and pivoted brace rods extending from the links and loosely connected with the blades near the free ends thereof, said brace rods of each pair extending in opposite directions. 50

4. The combination with the hull of a vessel, of chain propellers on one side of the vessel, each propeller having blades arranged in pairs on a common pivot so that either blade is active and the other inactive 55 according to the direction of travel of the propeller, and a differential gear interposed between said propellers and a source of power.

In testimony whereof I have hereunto set 60 my hand.

JOHN O. COOKE.
